UNITED STATES PATENT OFFICE.

GUSTAVE A. OVERSTROM, OF PASADENA, CALIFORNIA.

GAS AND OIL TRAP.

Application filed October 12, 1923. Serial No. 668,091.

This invention relates to traps designed to effect the separation of gas, oil, water and sand, or other constituents usually found in admixture with each other in the products issuing from oil wells.

The object of the invention is to provide a trap structure which is simple, economical to manufacture and efficient in operation.

Further object of the invention is to provide a trap for the purpose referred to, which is universal in operation, that is, is capable of use in handling the output of oil wells, whether of high, low or medium pressure or operated under vacuum.

Other objects of the invention will appear more fully hereinafter.

The invention consists in the location, combination and relative arrangement of parts, all as will be more fully hereinafter set forth, as shown in the accompanying drawings and finally pointed out in the appended claims.

Referring to the drawings,

Fig. 1 is a view in vertical central section of a trap structure, embodying the principles of my invention.

Fig. 2 is a transverse section of the same on the line 2—2 of Fig. 1 looking in the direction of the arrows.

Fig. 3 is a broken detailed view in vertical section on the line 3—3 of Fig. 2 looking in the direction of the arrows.

Fig. 4 is a broken detailed view in top plan of a corrugated or fluted and perforated baffle plate member employed in connection with my invention.

Fig. 5 is a broken detailed view in vertical section through the valve controlled gas outlet connection, at the upper end of the trap, the controlling valve being shown in open position.

Fig. 6 is a view similar to Fig. 5 showing the valve in closed position.

Fig. 7 is a broken detailed view in vertical section showing the valve controlled structure for the oil delivery connection at the lower end of the trap, the valve being in its closed position.

Fig. 8 is a similar view showing the valve in open position.

Fig. 9 is a broken detailed view showing the connection of the control valve stems or rods with the float member.

Fig. 10 is a detached detailed view in top plan of a form of float member, suitable for use in connection with my invention.

Fig. 11 is a view in section on the line 11—11 Fig. 10 looking in the direction of the arrows.

Fig. 12 is a view similar to Fig. 5 showing a slightly modified arrangement of gas outlet valve controlled structure, the valve being in its open position.

Fig. 13 is a view similar to Figs. 5 and 12 showing another slightly modified structure of gas outlet control valve arrangement.

Fig. 14 is a view in top plan of the structure shown in Fig. 13, and

Fig. 15 is a view in section on the line 15—15 of Fig. 13 looking in the direction of the arrows.

In my joint application with George Overstrom for gas and oil separators, Serial Number 649,396, filed July 5, 1923, issued as Patent No. 1,632,919 is shown, described and claimed a structure of gas and oil separator, which is more particularly designed and suitable for use under conditions of comparatively low pressure and low vacuum.

It is among the special purposes of my present invention to provide a structure which will operate under all conditions, from the lowest to the highest pressure, and from the lowest to the highest vacuum.

In the carrying out of my present invention, I propose to employ a separating or trap chamber in which is disposed to operate, a float member, which is suitably braced against collapsing under excessive pressures or excessive vacuum, and which is made sufficiently light and sensitive to permit operation thereof under the various actual conditions of pressure and vacuum encountered in the operation of oil wells. I also propose to employ valves to control the gas and oil outlet connections, which valves are operated directly by the float member without intervening lever connections, fulcrums, stuffing boxes or the like, and which valves are balanced under all pressures and are therefore independent of the pressure within the tank or gas or oil delivery lines.

I also propose to employ a structure wherein the float member is required merely to overcome frictional resistance in its operation. I also propose to provide a trap structure which is free from adjustments, to accommodate it to various pressure or vacuum conditions, thereby eliminating the element of human interference in adapting the structure to operate under the varying conditions encountered.

I also propose to provide a structure wherein the valves which control the gas and oil outlet connections, are readily and easily accessible from the outside of the tank 5 in order to facilitate repairs whenever required.

Another important feature of my invention is the provision in a trap structure of the nature referred to, of an oil outlet opening 10 into the tank at a height which is maintained at a point considerably above float level thereby enabling me to utilize fully the height of a tank for operation under vacuum, as well as pressure conditions without 15 excessive increase in size, dimension or weight of the float, and still maintain a large separating space for the oil and gas.

I also propose to provide a trap structure wherein a uniform flow of oil delivered into 20 the tank, is secured, such uniform flow being mainly towards the center of the tank, thereby producing uniform settling conditions throughout and preventing disturbing eddy currents, whirls and the like in the body of 25 the oil, which might result in a failure of efficient gas separation, and a consequent escape of gas through the oil outlet.

I also propose to provide a structure of trap wherein the float and valves carried 30 thereby are free to rotate axially as well as to rise and fall with variations in the level, thereby equalizing the wear thereof and preventing interruption of the operation through the sticking of these parts.

I also propose to provide a structure of 35 valves, particularly of the valve which controls the oil outlet connection in which abrasion due to fast flowing oil carrying particles of fine sand does not affect the efficiency of 40 the valve control.

I also provide means which are simple and effective to permit the escape of any gas accumulated from the mass of oil at the bottom of the tank.

I also propose to provide means to secure 45 an initial or preliminary settling and separation of the incoming oil, gas, water and sand as delivered from the well into the tank, and to provide means whereby the delivery of the incoming oil is effected into a 50 body of oil and sand within the tank, thereby breaking up and destroying or relieving, if not destroying, the cutting force of any sand carried in the emulsion delivered from 55 the well.

Another important and valuable feature 60 of my present invention is the provision in a trap structure of means to allow the full pipe opening for both the oil and gas delivery connections from the tank when the trap is working under normal conditions and the closing of the one or the other of the valves when an abnormal condition is encountered without closing either wholly or 65 partially the other of said valves.

In the accompanying drawings I have shown a trap structure in which these and various other features are incorporated.

Referring to the drawings, 20 is a shell of the tank, which for convenience in manufacture is preferably in the form of an elongated open ended cylinder, closed at its top by a cover 21, and at its bottom by the sand and water settling cone member 22. The mixture of gas, oil, sand and water, etc. from 70 the oil well is delivered into the tank somewhat above the middle of the tank cylinder 20, through the connection 23. Immediately above the connection 23, a man hole opening through the wall of the shell is provided 75 which is closed by detachable cover 24. Mounted within the shell 20 is what I term an overflow trough including a cylinder portion 25 which is centrally disposed with reference to the shell 20 and a depending cone portion 26 which is welded or otherwise secured at its lower and larger peripheral edge 80 to the inner wall of the shell 20.

The central cylindrical portion 25 of the overflow trough is disposed opposite the supply connection opening 23 and the upper open edge of said cylindrical portion extends slightly above said supply opening 23 while the cone shape portion 26 extends downwardly below the supply opening 23. This 85 forms an annular space 27 in which a preliminary separation of oil, sand, water and gas takes place. Such preliminary settling of the sand and water causes a bed of sand to be built up in the trough or space 27, and it is into the body of oil, sand and water thus built up within the space 27 that the incoming material is delivered. This 90 serves to break up the cutting force of the sand contained in the incoming emulsion and consequently reduces or prevents wear resulting from such cutting force.

In order to still further reduce the abrading or cutting action of the incoming sand delivered along with the emulsion into the tank upon the working parts of the apparatus, I provide an abrading plate or member 28 which is mounted upon the trough opposite the delivery opening 23.

This wearing plate 28 is made removable 115 so that when worn through the cutting action of the incoming sand it may be removed and replaced by a new wearing plate, the man hole cover 24 being removed for the purpose of permitting the removal and insertion of 120 the wearing plate 28.

In order to prevent any undue splash of the incoming stream of material over the top edge of the cylindrical portion 25 of the cone trough, I provide the cone trough of the upper end of the cylindrical portion 25 thereof, with an apron 29 which extends laterally from the portion 25 of the trough and towards the incoming material delivery opening 23, said apron having an upturned edge 125 130

flange 30 which is positioned in proximity to the inner surface of the shell 20 above the delivery opening 23. The provision of this apron 29 and its upturned flange 30 causes the incoming flow of material to flow annularly around the upper end of the trough and eventually to spill over the upper edge of the cylindrical portion 25 thereof, into the space within the tank below said trough. Openings 31 are formed through the cone portion 26 of the trough adjacent its lower edge to permit a part of the accumulated preliminary settlement in the annular space 27, consisting mainly of sand and water to drip through the cone 26 into the lower portion of the shell, instead of being carried up and spilling over the upper edge of the cylindrical portion 25. Of course when there is an absence of water in the mixture delivered into the tank, some of the oil will drip through the opening 31. In practice, I prefer to omit any drip openings 31 at points directly beneath the opening 23. This results in the building up of a mass of sand, oil and water in the space 27 opposite the inlet opening 23. The incoming stream of oil, water, sand and gas impinges upon this built up body thereby breaking up the force of the incoming stream, before it reaches the wearing plate 28, its energy being expended against and absorbed by the mass of collected sand, water and oil. I regard this as a valuable feature of my invention, particularly when very high pressures of incoming material are to be handled as it substantially increases the life of the apparatus, and moreover by requiring the greater portion of the incoming material to rise above the level of the inlet opening, and to spill over the upper edge of the cylindrical portion 25 of the trough, and the provision of the apron 29 to prevent splashing of the incoming mass, I am enabled to secure a uniform overflow of the incoming material, all the way around the upper edge of the portion 25 of the trough. The water being heavier than the oil sinks readily to the bottom of the trough together with the sand, and possibly some of the oil, when little or no water is present in the mixture delivered.

As above indicated, the water, sand and oil, if any, which thus collects in the trough and space 27, or a portion thereof, drip through the openings 31 in comparatively small streams, which are distributed at desirable distances apart all the way around the interior wall of the shell, except, as explained, at points directly beneath the inlet opening 23.

These small trickling streams of water, or water and oil, or oil as the case may be, carry with them a portion of the sand, particularly where fine sand is encountered. The large particles of sand fall by gravity into the

main body of oil contained in the tank, thus gaining acceleration in the fall thereof, and hence increasing their settling velocity after reaching the oil beyond what it would have if allowed to run down the inner wall surface of the shell along with the regular downflow of oil. 70

This operation enables the incoming sand and water or a portion thereof to quickly reach the lower part of the tank, and leaving 75 comparatively little sand or water to be carried along with the current of oil towards the center of the tank, and the overflow thereof into the upper open end of the portion 25 of the trough. There is comparatively small danger of the openings or holes 31 becoming plugged or filled up so long as these holes are of greater diameter than the thickness of the member 26 in which they are formed. Some of the oil which overflows into the upper open end of the portion 25 of the trough, will drip into the tank from the point 32 and fall down on to the upper end surface of the float below, and presently 80 to be described, and will follow down the outside wall of the float into the lower portion of the tank. 85

Other portions of the oil which spills over into the open upper end of the trough will run down the inside surface of the cone portion 26 until it reaches the inner wall of the shell and then will flow down the shell surface. That part of the oil which drips from the point 32 as well as that part which flows down the inner wall of the shell will not 90 materially interfere with the settling of the water and sand or water, oil and sand which drips through the holes 31. 95

By the arrangement described I am enabled to secure a more efficient and rapid 105 separation, and the danger of carrying sand over into the oil up-take presently to be described is minimized. The sand and water which collect in the cone shaped portion 22 at the lower end of the tank is drawn off 110 therefrom in any suitable or convenient manner, as for instance through outlet 33. If desired, this outlet 33 may be connected to the usual sand drums (not shown) according to preferred practice. 115

The gas which separates out from the oil, sand and water, will rise into the upper part of the tank where it may, if desired, be passed over baffles or through scrubbers to insure further separation of gas from any 120 enclosing molecules of oil. Inasmuch as the gas frequently becomes enclosed within minute oil bubbles, which by reason of their buoyancy rise with the stream of separated gas, I have found it desirable to provide 125 means for puncturing such minute bubbles so as to permit the enclosed gas to escape. Ordinarily baffles variously disposed and arranged or scrubbers, are depended on to accomplish this result. 130

I have found, however, that in practice, ordinary baffle plates or scrubbing arrangements are inefficient and I have conceived the idea of providing means whereby such gas carrying oil bubbles are punctured. To accomplish this result I caused the ascending column of gas to pass through a series of inverted cone shaped disks or plates 33, which are disposed within the shell 20 at the upper end thereof, the successive cone plates being disposed respectively over each other. Each of these plates is preferably corrugated or fluted radially as indicated at 34, and I form roughened punch holes or perforations with roughened edges indicated at 35 through the raised ridges of the fluted plates 33.

In practice the lower open ends of the successive plates 33 are of decreasing size or diameter towards the upper end of the shell, these openings being preferably centrally disposed with relation to the shell. The gas volume impinging against the under surface of the successive corrugated or fluted members follows such surfaces and are deflected by the lower closed channels of said members into the intermediate upper channels, or ridges, which are perforated with the holes with roughened edges and passing through such rough edge openings any bubble of oil filled with gas will become punctured thereby releasing the gas and permitting the oil, when the gas is released, therefrom, to trickle back into the shell down the lower inclined surfaces of the fluted members.

I will now describe the gas outlet and oil outlet connections. These connections are located respectively at the upper and lower ends of the trap. Their structures are identical and therefore a detailed description of the one will apply equally as well to the other.

Attached at each end of the trap is a T connection 36, with a horizontal outlet or outlet opening 37, the upper one for gas and the lower one for oil. Disposed in each T connection or the head portion of such T is a sleeve 38 having one or more openings 39 into an annular channel 40 formed in the head of the T connection 36, and which registers with the outlet opening 37. The outer end of each of the T connections 36 is closed by a cover plate 41. Fitting and operating within each sleeve 38 is a cylinder slide valve 42. These valves are open at both ends, and therefore are balanced valves. To each valve 42 at a point at the interior thereof is connected a rod 43 which connects the valves to the cap 44 of the float member, whereby the valves are operated up and down in unison by the float. The connection of the rods 43 to the valves 42 may be effected in any suitable or convenient manner. I have shown spiders 45 mounted within each valve 42, and connected thereto,

the respective remote ends of the rods 43 being anchored in the hub portions of the spiders 45.

The valves 42 are so spaced apart with relation to each other and so assembled with relation to the sleeves 38, and delivery openings 37 with which they cooperate that when one valve is in closed position, as shown at the bottom for example in Fig. 1, the other valve is in wide open position, and when the valves are shifted by the float, the valves are carried into position to permit both outlet connections 37 to be wide open at the same time.

By reason of this arrangement it will be seen that when one of the valves closes its outlet, the other remains wide open, no matter which outlet is closed. In other words, when one valve closes the other is not opened, but remains open. Consequently according to the operation of the float within the tank, either one or the other of the outlet openings 37 may be opened and closed, while the other outlet opening remains open during both operations.

In Fig. 5 I have shown the gas control valve 42 in open position, while in Fig. 6 the same valve is shown in closed position.

In Fig. 7 I have shown the oil control valve 42 in closed position with reference to its delivery opening 37, and in Fig. 8 I have shown the same valve in open position.

Instead of providing the sleeve 38 with a series of openings 39, each open into the annular channel 40, and whether for the gas or the oil control valve structure, I have shown such sleeve 38' in Fig. 12 as provided with a single opening 39' in the wall thereof, which is disposed diametrically opposite the delivery opening 37. Such a structure reduces any tendency to leak, although it slightly, although inappreciably increases the friction of the operation. Such a structure and arrangement, however, I desire to include within the scope of my invention.

The float to which the valve rods 43 are connected may be of any suitable or desired structure. In the form shown, the float consists of a cylindrical member or portion 46 disposed within the shell 20 below the cone trough structure above described. The ends of this cylindrical portion are closed by the cover portions 47. These are inclined or cone shaped and are oppositely disposed with reference to each other, the larger ends of the cones being received in the open ends of the cylindrical portion 46. Extending centrally through the cylindrical portion 46, and through central openings in the cone portions 47, is a cylindrical member 48, the lower end of which terminates in the mouth or opening of the lower cone member cover 47. The upper end of the cylinder 48 projects through the upper cone cover member 47 and up into the cylindrical portion 25 of

the overflow trough, when the oil delivery control valve is in its closed position as shown in Fig. 1. The extreme upper end of the tubular member 48 is closed by the cap 44 to which as above explained, the piston rods 43 are connected. The lower end of the tubular member 48 opens freely into the lower portion of the shell. If desired and preferable, a check valve 49 which seats inwardly is mounted in the cap 44. Extending up through the lower open end of the tubular member 48 is an oil delivery pipe connection 50, the upper end of which extends well up near the upper closed end of tubular member 48. This oil delivery pipe connection communicates in a suitable manner through the valve controlled openings 39, 39' with the oil delivery opening 37. Mounted within the tubular member 48 and extending longitudinally thereof are wings 51 which serve the purpose of guiding the float structure in its up and down movement, and maintaining the same in centered relation with respect to the delivery pipe connection 50.

In order to still further center and guide the float in its up and down movements, suitable rollers 52 may, if desired, be mounted upon the inner wall of the shell 20, to engage, guide and center the cylindrical portion 46 of the float. Likewise guiding members 53 may be arranged within the overflow trough members 25, 26 to engage, guide and center the tubular member 48 of the float.

Instead of the oil delivery T connection 36 being applied directly to the lower end of the cone portion 22 of the shell, I prefer to employ a member 54 the outer wall of which is fastened to the lower end of the cone member 22, and against the lower end of which member 54 the T fitting is applied. This member 54 is provided with a central upwardly extending tubular section 55, to the upper end of which is fastened the lower end of the oil delivery pipe 50. The structure just described is simple and efficient, and enables the parts to be economically manufactured and quickly and easily assembled, or detached and removed where necessity therefor arises. In the structure shown, it will be seen that the sleeve member 38, or the upper end thereof, extends up into the central tubular portion 55 of the closure member 54.

The valve rods 43 may be connected to the cap 44 of the float structure in any suitable or convenient manner. In Fig. 9 I have shown a simple and efficient structure for this purpose, wherein the cap 44 is provided with a central boss 56, through which is formed a threaded bore. Oppositely disposed studs 57, have threaded shanks 58 which are screwed into this threaded bore until their ends abut against each other. One

of the studs 57 may shoulder against one end of the boss 56, while the set nut 59 carried by one of the threaded shanks 58 abuts against the other end of the boss, thus clamping and rigidly holding the studs in position.

When thus assembled, a hole 60 is drilled transversely through the faces or abutting surfaces of the threaded ends 58 and through the boss 56, to receive a transversely extending pin, thereby locking the studs in assembled position against relative rotative displacement and hence likewise holding the piston rods and valves against relative rotary movement. The piston rods 43 are shown tubular, and the approximate ends of said rods slip over the studs 57 and are fastened thereon by transversely extending pins 61. Thus I provide an exceedingly strong, durable connection of the piston rods, together, and to the float structure in rigid relation. The parts are simple and easily constructed and assembled.

In practice I prefer to provide the top cover or plate 21 of the trap shell with an opening 62, to which, if desired, a safety valve may be attached.

If required and preferably, the cylindrical portion 46 of the float may be braced internally against the collapsing action of externally applied pressures. For this purpose I have shown a bracing ring member 63 disposed within the float member 46.

In case of the accumulation of dirt, or other foreign substances, particularly in the lower portion of the oil delivery T 36, the same may be removed by providing the closure cap 41 of said T connection with an opening 64 for connection thereto of a suitable drain connection or stop cock.

It may sometimes be desirable to be able to observe the position of the float within the shell. To permit this I provide a rod 66, (see Fig. 13) connected to the valve 42, or the spider 45 thereof, and which extends vertically through an opening 67 formed in the cap 41 at the upper end of the T connection. In order to avoid the necessity for the provision of a stuffing box I prefer to screw a transparent tubular member 68 into the opening 67 of cap 41, the extreme upper end of said transparent tube being closed by a cap 69 and the upper end of the rod 66 works in this closed tube 68, thereby enabling the position of the float to be ascertained at a glance at any time during the working of the apparatus.

It may sometimes be desirable to test the movement of the float to ascertain whether or not it is freely movable, and to prevent the possibility of the same becoming stuck. In Fig. 13 I have shown an arrangement which will permit these results to be accomplished and wherein a standard is mounted on the cap 41, which closes the

open ends of the gas outlet T connection, said standard being provided with vertically spaced pins 71. By removing the tubular member 68, the lever 72 provided with a hooked end which engages one or another of the pins 71 is arranged to bear intermediate its ends upon the upper end of rod 66. By pulling down the lever 72 when so arranged, the float will be pushed down against the lifting action of its buoyancy thereby testing out the freedom of vertical movement of the float, and preventing the float from becoming stuck against free vertical movement.

15 I may sometimes be desirable to positively lock the cap which closes the upper end of the cylindrical portion 48 of the float structure against rotative movement with respect to said tubular member 48.

20 In Figs. 10 and 11 I have shown means for accomplishing this purpose wherein the cap member 44' has a pawl or dog 74 pivotally mounted upon its outer surface, the free end of said dog being adapted to engage 25 one or another of slots 75' in the upper end surface of the tubular member 48.

In some types of float structures, in place of the bottom wall of the float being cone shaped as formed by the cone 47 shown in 25 Fig. 1, the said bottom wall may be concaved forming an annular chamber 75 in the bottom wall surface of the float as shown in Fig. 11. With such a structure it sometimes occurs that gas, which is not separated 30 from the oil in the upper part of the trap, will accumulate in the space 75 thereby altering the buoyancy of the float and interfering with its proper operation. To prevent this in such a type of float, suitable pipe connections 76 extend vertically 35 through the float chamber and the interior bracing rings 77 thereof, which pipes open free communication between the annular chamber 75 and the space within the casing 40 20 above the float.

45 It will be understood that the buoyancy level of the float is substantially at the mid length point of the float as indicated by the dotted line AA in Fig. 1. At the dotted line BB in Fig. 1 is indicated the buoyancy level 50 of the float within the shell 20 at which the float exerts its maximum upward thrust and the level indicated at the dotted line CC in Fig. 1 corresponds with the buoyancy 55 level of the float when the float is exerting its maximum downward pull.

It will be observed that the only work 60 which the up and down movements of the float are required to perform, is the shifting of the valves 42. Since these valves are balanced only the frictional resistance thereof in their movements in sleeves 38 is to be overcome. Ordinarily this frictional resistance is figured at about eighty pounds, 65 whereas the float is proportioned to exert

an upward push and a downward pull of approximately three hundred and twenty pounds, or about four times the amount of the friction of the valves 42, thus providing a factor of safety of four. Consequently 70 the oil levels in the casing 20 will fluctuate but very little, and may never attain the levels BB or CC except under abnormal conditions of oil flow.

In operation, starting with an empty trap, 75 the oil outlet 37 from the trap is closed. The mixture of oil, gas, water, sand and the like from the oil well is then delivered into the trap through the connection 23. The incoming stream of the mixture flows into 80 and fills the annular space 27 which surrounds the overflow trough device, thereby permitting a preliminary settlement of sand and water into the space 27 so as to build up, particularly at a point opposite the inflow 85 opening 23, a bed of sand and water and possibly some oil, to receive the impact of the incoming stream of the mixture.

The level of the oil rises in the annular space 27 until the oil finally spills over the 90 upper open end of the portion 25 of the overflow trough being thereby delivered uniformly and without eddies or whirls, into the chamber of casing 20 below the overflow trough, the sand and water, and perhaps some oil, dripping through the openings 31 of the overflow trough into the tank beneath said trough.

The apron 29, with its upturned flange 30, prevents the incoming oil flow from 100 splashing over the upper edge of the overflow trough and directs the flow of incoming oil annularly into and around the space 27, thereby also aiding in breaking up any eddies and whirls and enabling a uniform 105 overflow of the oil over the upper edge of the overflow trough and into the trap chamber. If it be assumed that the mixture is delivered into the trap at a comparatively 110 low pressure, say for example, at a pressure of one pound, the oil accumulates in the trap chamber or in the lower part thereof until the float begins to rise. Therefore, no oil 115 can reach the oil outlet connections 37 at the bottom of the trap for the reason that the pressure within the tank is insufficient to cause the oil to rise up from the lower part of the casing through the bore of the cylinder member 48 of the float to a height sufficient for such oil to spill over into the 120 oil outlet pipe connection 50. Consequently the float structure will continue to rise as oil accumulates in the trap until eventually the valve 42 which controls the gas outlet 125 is closed. The closure of this valve increases the pressure within the trap sufficiently to force the oil in the trap chamber up through the bore of the tubular member 48 of the float to a height enabling it to spill over into the upper end of the oil de- 130

livery connection 50, the level of the oil in the tank correspondingly falling.

When the oil spills over the upper open end of the oil delivery pipe connection 50, a siphonic action is inaugurated which would drain out the oil from the trap if the oil flow is only light, but since the lowering of the level of the oil in the trap resulting from the flow of the oil into the oil delivery pipe connection 50 is resulted in lowering the float, the gas valve 42 at the top of the trap is again opened, and consequently the pressure within the trap is reduced by the resulting delivery of gas from the trap through the gas delivery connection 37. The result will be that the float will descend thereby closing gradually the oil control valve 42 until a balanced condition of pressure within the tank is again obtained. The same operation takes place whatever may be the pressure under which the mixture is delivered into the trap as well as in the operation of the trap under vacuum conditions.

In practice it has been found that there is usually some gas pressure delivered from an oil well, and if the trap is to operate on a vacuum, such vacuum is produced by suction from suitable gas compressors or the like, introduced into the gas delivery connection.

In such case, starting with the trap empty, the suction is started and the oil will fill up within the tank outside of the float, and also will rise within the central bore of tubular member 48 of the float as the air and gas escapes from the trap and from the float through the check valve 49. When, however, the buoyancy level of the float is reached, the float will gradually rise, thereby shutting off the suction and hence building up the pressure within the trap sufficiently to elevate the oil level within the tubular member 48, until it eventually spills over into the oil delivery pipe connection 50. This starts the delivery flow of the oil from the trap which produces a suction on the oil, and the float will then start to descend again, thereby again opening more or less the gas delivery valve 42, thereby relieving the pressure within the trap in the same manner as above described with low pressure delivery of the mixture into the trap.

Where the mixture is delivered into the trap under high pressure, the oil will rise through the central bore of the tubular member 48 of the float, as fast as the check valve 49 permits the escape of air and gas therefrom, thereby enabling the oil level in said bore to quickly reach the top of the oil delivery pipe connection 50 and spill over the upper open end of the same.

Thus it will be seen that in practically most instances encountered in practice, the oil influx controls the oil level within the trap. This level will rise and fall accord-

ing to the float control of the balanced valves 42 which respectively control the oil and gas delivery connections 37. If the oil flow into the trap increases, the float will rise thereby shifting the oil delivery control valve and permitting a correspondingly increased amount of oil to flow from the trap. If the oil flow decreases, the oil level within the trap will correspondingly fall. Meanwhile the gas outlet remains wide open until a rush of oil delivery into the trap takes place of such volume that the oil outlet pipe wide open cannot take care of the oil delivery flow from the trap. When this takes place the oil rises above the buoyancy level of the float and the gas outlet is closed off. As soon as the oil flow falls to a point where the oil delivery pipe connection can take care of the oil delivery from the trap, the float will again drop down gradually and the gas control valve will open and the delivery of gas will result.

Ordinarily a sufficient amount of oil, after the operation has been started, accumulates within the bore of the tubular member 48 of the float to prevent violent fluctuations or up and down movements of the float.

The provision of the longitudinally extending vanes or members 51, on the inner wall surface of the bore of tubular member 48 of the float, tends to prevent any undue fluctuations or whirls within the column of oil which ascends through this bore.

It is obvious that many of the details which I have shown and described are not essential, and in some cases may be omitted all together.

From the foregoing description it will be seen that I provide an exceedingly simple and efficient trap structure which is universal in operation, that is, which may be employed to handle either high pressure, medium pressure or low pressure, or even vacuum operation without requiring any adjustments or special care or attention on the part of attendants, thus eliminating the possibility of human error in the handling of the apparatus.

It will also be seen that I provide for breaking up and preventing the formation of eddies or whirls in the mixture or emulsion handled by the apparatus. The structure is economical to manufacture and assemble. It is automatic in operation and except for the control of the discharge connections requires no special attention when in operation.

Having now set forth the objects and nature of my invention, and structures embodying the principles thereof, what I claim as new and useful, and of my own invention and desire to secure by Letters Patent is:

1. In a trap for separating the products delivered from oil wells, a casing into which such products are delivered, said casing hav-

- ing gas and oil outlet connections, a float arranged within said casing, valves connected to said float to respectively control said openings, a transparent closure closed at its outer end and communicating at its inner end with said casing, and a rod carried by the float and extending into said closure.
2. In a trap of the class described, a casing having an inlet opening through the side wall thereof, and gas and oil outlet openings respectively disposed at the upper and lower ends thereof, a float, and valves connected to said float to respectively control said outlets, in combination with fluted plates successively disposed the one above another in said casing above the inlet opening and below the gas outlet opening, said fluted plates having roughened perforations therethrough.
3. In a trap of the class described, a casing having an inlet opening through the side wall thereof, and gas and oil outlet openings respectively disposed at the upper and lower ends thereof, a float, and valves connected to said float to respectively control said outlets, in combination with fluted plates successively disposed the one above another in said casing above the inlet opening and below the gas outlet openings, said fluted plates being perforated through the raised ridges of the flutes thereof.
4. In a trap of the class described, a casing having an inlet opening through the side wall thereof, and gas and oil outlet openings respectively disposed at the upper and lower ends thereof, a float and valves connected to said float to respectively control said outlets, in combination with fluted plates successively disposed the one above another in said casing above the inlet opening and below the gas outlet openings, said fluted plates being of disked or conical form with central openings therethrough.
5. In a trap of the class described, a casing having an inlet opening through the side wall thereof, and gas and oil outlet openings respectively disposed at the upper and lower ends thereof, a float and valves connected to said float to respectively control said outlets, in combination with fluted plates successively disposed the one above another in said casing above the inlet opening and below the gas outlet openings, said fluted plates being of disked or conical form with central openings therethrough, the central openings in said plates being of decreasing diameter towards the upper end of the casing.
6. In a trap of the class described, a casing having gas and oil outlets respectively disposed at the upper and lower ends of said casing, valves to control said outlets, a float structure arranged for free movement in said casing, said float structure in- cluding a cap member, and rods secured to said cap member and having connection, respectively with said valves.
7. In a trap of the class described, a casing having gas and oil outlets respectively disposed at the upper and lower ends of said casing, valves to control said outlets, a float structure arranged for free movement in said casing, said float structure including a cap member, and rods secured to said cap member and having connection respectively with said valves, and means to lock said rods against displacement relatively to each other.
8. In a trap of the class described, a casing having gas and oil outlets respectively disposed at the upper and lower ends of said casing, valves to control said outlets, a float structure arranged for free movement in said casing, said float structure including a cap member, and rods secured to said cap member and having connection respectively with said valves, and means to lock said cap member against rotation movement relative to the float structure.
9. In a trap of the class described, a casing having gas and oil outlets respectively disposed at the upper and lower ends of said casing, valves to control said outlets, a float structure arranged for free movement in said casing, said float structure including a cap member, having a central hub boss, screw plugs fitted in said boss, and rods connected to said screw plugs and to said valves.
10. In a trap of the class described, a casing, a float structure disposed therein and having a closed body portion and a tubular member extending centrally through the body portion to a point above the latter, the upper end of the tubular member being closed and the lower end freely opening into the casing chamber below the float, an oil delivery pipe connection extending into said tubular member through the lower open end thereof and to a point above the float body, and an oil outlet from the casing communicating with the lower end of said delivery pipe connection.
11. In a trap of the class described, a casing, a float structure disposed therein and having a closed body portion and a tubular member extending centrally through the body portion to a point above the latter, the upper end of the tubular member being closed and the lower end freely opening into the casing chamber below the float, an oil delivery pipe connection stationarily held and extending into said tubular member through the lower open end thereof and to a point above the float body, an oil outlet from the casing communicating with the lower end of said delivery pipe connection, and a valve connected to the float structure and

operating to control the communication between said delivery pipe connection and said outlet.

12. In a trap of the class described, a casing, a float structure disposed therein and having a closed body portion and a tubular member extending centrally through the body portion to a point above the latter, the upper end of the tubular member being closed and the lower end freely opening into the casing chamber below the float, an oil delivery pipe connection extending into said tubular member through the lower open end thereof and to a point above the float body, longitudinally extending wings or vanes disposed in the space between said tubular member and the delivery pipe connection, and an oil outlet from the casing communicating with the lower end of said delivery pipe connection.

13. In a trap of the class described, a casing, a float structure disposed therein and having a closed body portion and a tubular member extending centrally through the body portion to a point above the latter, the upper end of the tubular member being closed and the lower end freely opening into the casing chamber below the float, an oil delivery pipe connection extending into said tubular member through the lower open end thereof and to a point above the float body, a check valve in the closed end of said tubular member, and an oil outlet from the casing communicating with the lower end of said delivery pipe connection.

14. In a trap of the class described, a casing, a float structure disposed therein and having a closed body portion and a tubular member extending centrally through the body portion to a point above the latter, the upper end of the tubular member being closed and the lower end freely opening into the casing chamber below the float, an oil delivery pipe connection extending into said tubular member through the lower open end thereof and to a point above the float body, a fitting having an outer wall portion secured to the lower end of the casing and a central tubular portion fitted to the lower end of said delivery pipe connection, a T head fitting secured to the lower end of said fitting and communicating with said tubular portion, said T head fitting having an oil outlet opening therefrom.

15. In a trap of the class described, a casing, a float structure disposed therein and having a closed body portion and a tubular member extending centrally through the body portion to a point above the latter, the upper end of the tubular member being closed and the lower end freely opening into the casing chamber below the float, an oil delivery pipe connection extending into said tubular member through the lower open end thereof and to a point above the float body,

a fitting having an outer wall portion secured to the lower end of the casing and a central tubular portion fitted to the lower end of said delivery pipe connection, and a valve connected to said float structure and operating to control said oil outlet opening.

16. In a trap of the class described, a casing, a float structure disposed therein and having a closed body portion and a tubular member extending centrally through the body portion to a point above the latter, the upper end of the tubular member being closed and the lower end freely opening into the casing chamber below the float, an oil delivery pipe connection extending into said tubular member through the lower open end thereof and to a point above the float body, a fitting having an outer wall portion secured to the lower end of the casing and a central tubular portion fitted to the lower end of said delivery pipe connection, a T head fitting secured to the lower end of said fitting and communicating with said tubular portion, said T head fitting having an oil outlet opening therefrom, a sleeve fitting in said T head and extending into said tubular portion, said sleeve having an opening in communication with said oil outlet opening, and a valve disposed in said sleeve and connected to said float structure for controlling said communication.

17. In a trap of the class described, a casing, a float structure disposed therein and having a closed body portion and a tubular member extending centrally through the body portion to a point above the latter, the upper end of the tubular member being closed and the lower end freely opening into the casing chamber below the float, an oil delivery pipe connection extending into said tubular member through the lower open end thereof and to a point above the float body, a fitting having an outer wall portion secured to the lower end of the casing and a central tubular portion fitted to the lower end of said delivery pipe connection, said fitting having communication with an oil outlet opening, a drain connection through the wall portion of said fitting, and a valve operating in said fitting and connected to the float structure to control the oil outlet opening.

18. In a trap for separating the products delivered from oil wells, a casing having an inlet opening through the side wall thereof through which the products to be separated are delivered into the casing, said casing having gas and oil outlets respectively disposed at the upper and lower ends thereof, a float structure disposed within said casing, and valves connected thereto for respectively controlling said gas and oil outlets, in combination with an overflow trough structure disposed within the casing above the float structure and opposite said inlet opening.

19. In a trap for separating the products

delivered from oil wells, a casing having an inlet opening through the side wall thereof through which the products to be separated are delivered into the casing, said casing having gas and oil outlets respectively disposed at the upper and lower ends thereof, a float structure disposed within said casing, and valves connected thereto for respectively controlling said gas and oil outlets, in combination with an overflow trough structure disposed within the casing above the float structure and opposite said inlet opening, said overflow trough structure including an upper tubular portion and a lower conical portion to provide an annular trough or space between said overflow structure and the inner wall of the casing.

20. In a trap for separating the products delivered from oil wells, a casing having an inlet opening through the side wall thereof through which the products to be separated are delivered into the casing, said casing having gas and oil outlets respectively disposed at the upper and lower ends thereof, a float structure disposed within said casing, and valves connected thereto for respectively controlling said gas and oil outlets, in combination with an overflow trough structure disposed within the casing above the float structure and opposite said inlet opening, said overflow trough structure including an upper tubular portion and a lower conical portion to provide an annular trough or space between said overflow structure and the inner wall of the casing, said lower conical portion having drain openings therethrough from said trough into the casing.

21. In a trap for separating the products delivered from oil wells, a casing having an inlet opening through the side wall thereof through which the products to be separated are delivered into the casing, said casing having gas and oil outlets respectively disposed at the upper and lower ends thereof, a float structure disposed within said casing, and valves connected thereto for respectively controlling said gas and oil outlets, in combination with an overflow trough structure disposed within the casing above the float structure and opposite said inlet opening, said overflow trough structure including an upper tubular portion extending to a plane above the inlet opening, and a lower conical portion connecting at its lower edge to the inner wall of the casing.

22. In a trap for separating the products delivered from oil wells, a casing having an inlet opening through the side wall thereof through which the products to be separated are delivered into the casing, said casing having gas and oil outlets respectively disposed at the upper and lower ends thereof, a float structure disposed within said casing, and valves connected thereto for respec-

tively controlling said gas and oil outlets in combination with an overflow trough structure disposed within the casing above the float structure and opposite said inlet opening, said overflow trough structure including an upper tubular portion extending to a plane above the inlet opening, and a lower conical portion connecting at its lower edge to the inner wall of the casing, and a splash apron extending laterally from the upper edge of said tubular portion towards the inner wall of said casing, above said inlet opening.

23. In a trap for separating the products delivered from oil wells, a casing having an inlet opening through the side wall thereof through which the products to be separated are delivered into the casing, said casing having gas and oil outlets respectively disposed at the upper and lower ends thereof, a float structure disposed within said casing, and valves connected thereto for respectively controlling said gas and oil outlets in combination with an overflow trough structure disposed within the casing above the float structure and opposite said inlet opening, said overflow trough structure including an upper tubular portion extending to a plane above the inlet opening, and a lower conical portion connecting at its lower edge to the inner wall of the casing, and a splash apron extending laterally from the upper edge of said tubular portion towards the inner wall of said casing, above said inlet opening, said apron having an upturned flange at its outer edge.

24. In a trap for separating the products delivered from oil wells, a casing having an inlet opening through the side wall thereof through which the products to be separated are delivered into the casing, said casing having gas and oil outlets respectively disposed at the upper and lower ends thereof, a float structure disposed within said casing, and valves connected thereto for respectively controlling said gas and oil outlets, in combination with an overflow trough structure disposed within the casing above the float structure and opposite said inlet opening, said overflow trough structure including an upper tubular portion and a lower conical portion to provide an annular trough or space between said overflow structure and inner wall of the casing and a wearing plate carried by said overflow trough structure and disposed opposite said inlet opening.

25. In a trap for separating the products delivered from oil wells, a casing having an inlet opening through the side wall thereof through which the products to be separated are delivered into the casing, said casing having gas and oil outlets respectively disposed at the upper and lower ends thereof, a float structure disposed within said casing, and

valves connected thereto for respectively controlling said gas and oil outlets, in combination with an overflow trough structure disposed within the casing above the float structure and opposite said inlet opening, said overflow trough structure including an upper tubular portion and a lower conical portion to provide an annular trough or space between said overflow structure and inner wall 10 of the casing and a wearing plate carried by said overflow trough structure and disposed opposite said inlet opening, said wearing plate being detachable and removable.

26. In a trap for separating the products delivered from oil wells, a casing having an inlet opening through the side wall thereof through which the products to be separated are delivered into the casing, said casing having gas and oil outlets respectively disposed at the upper and lower ends thereof, a float structure disposed within said casing, and valves connected thereto for respectively controlling said gas and oil outlets, in combination with an overflow trough structure disposed within the casing above the float structure and opposite said inlet opening, said overflow trough structure including an upper tubular portion and a lower conical portion to provide an annular trough 30 or space between said overflow structure and inner wall of the casing and a wearing plate carried by said overflow trough structure and disposed opposite said inlet opening, said wearing plate being detachable and removable, said casing having a man hole opening through the wall thereof above said inlet opening.

27. In a trap for separating the products delivered from oil wells, a casing having an inlet opening through the side wall thereof through which the products to be separated are delivered into the casing, said casing having gas and oil outlets respectively disposed at the upper and lower ends thereof,

a float structure disposed within said casing, 45 and valves connected thereto for respectively controlling said gas and oil outlets in combination with means to build up a mass of the products delivered into the casing, at a point opposite said inlet opening, to receive the 50 impact of the incoming products.

28. In a trap for separating the products delivered from oil wells, a casing having an inlet opening through the side wall thereof through which the products to be separated 55 are delivered into the casing, said casing having gas and oil outlets respectively disposed at the upper and lower ends thereof, a float structure disposed within said casing, and valves connected thereto for respectively controlling said gas and oil outlets in combination with means to form an annular channel or trough within the casing opposite said inlet opening and above said float, and into which channel the incoming products are delivered.

29. In a trap for separating the products delivered from oil wells, a casing having an inlet opening through the side wall thereof through which the products to be separated 70 are delivered into the casing, said casing having gas and oil outlets respectively disposed at the upper and lower ends thereof, a float structure disposed within said casing, and valves connected thereto for respectively controlling said gas and oil outlets in combination with means to form an annular channel or trough within the casing opposite said inlet opening and above said float, and into which channel the incoming products are 75 delivered, said channel delivering over its upper edge into the lower portion of the casing.

In testimony whereof I have hereunto set my hand on this 4th day of October, A. D. 85 1923.

GUSTAVE A. OVERSTROM.
